United States Patent Office

Des. 205,883
Patented Oct. 4, 1966

205,883

SHOE

Carole Post, 2895 Riverside Drive, Bellmore, N.Y.

Filed Oct. 11, 1965, Ser. No. 87,420

Term of patent 3½ years

(Cl. D7—7)

I claim:

The ornamental design for a shoe, as shown.
